FLAT KNITTING FRAME

Application filed September 24, 1926, Serial No. 137,585, and in Germany September 1, 1925.

My invention relates to flat knitting frames provided with means for altering the stroke of the slurcocks in accordance with the width of the fabric to be made. By this means a substantial increase in the output of flat knitting frames is obtained.

Instead of guiding the slurcocks in the usual manner of manufacture of stockings always over the whole width of the fabric regardless whether a welt is made or during the manufacture of the narrowed length or the tip of the stocking only a part of the sinkers is operative for sinking the loops, the stroke of the slurs is according to the invention altered to correspond to the width of the fabric.

The stroke of the slurcocks is preferably not changed after each row of loops has been made but may be altered in greater intervals between the rows of loops. With the new arrangement it is possible to reduce the time required to drive the slurcocks as the machine parts associated with the slurcocks need be moved only through a distance which the slurcocks are actually required to travel in manufacturing the fabric.

At the end of the stroke of the slurcocks necessary for carrying out the knitting process, the slurcocks must be moved out of the working line in order that the sinkers may be retracted.

This alteration of position is required by reason of the fact that the slurcocks are not moved beyond the end of the sinker bed, the extent of movement of the slurcocks being regulatable to conform approximately to the width of the fabric.

In the accompanying drawing one mode of carrying out the invention is shown diagrammatically in plan view.

The slur bar 1 carries the slurcocks 2 and is moved by the cam 3. This cam 3 which is diagrammatically illustrated, cooperates with an arm 4 of a bell crank lever pivotally mounted at 5 on the frame of the knitting machine. The other arm 6 of the bell crank lever is provided with a slot 7. A lever 9 pivoted at 8 is connected to the slur bar 1. Pivotally connected to the lever 9 is a rod 10 the free end of which carries a guide

block 11 sliding in the slot 7. An arm 13 of a double lever 13, 15 pivoted at 12 is connected by means of an intermediate rod 14 to the rod 10. The other arm 15 of the double lever 13, 15 is formed as a handle. 55 Below the arm 15 an adjustment scale is provided.

The slurcocks 2 are slidable in guides 17 extensions of which serve as bearings for a rod 18. In the level of each slurcock the rod 18 is provided with a crank 19 which is connected to the slurcock 2 by means of a rod 20.

A toothed drum 21 is arranged at the end of the bar 18 opposite the mechanism for shifting the slur bar 1. Pivotally mounted in the frame of the knitting machine is a rack 22 which engages the drum 21. The drum 21 is of such a length that, even if the slur bar 1 is shifted longitudinally to the end 70 of either stroke, the rack 22 will engage the teeth of the drum 21.

The rack 22 is moved by a cam 23 cooperating with an arm 24 of a bell crank lever 24, 26 pivoted at 25. The arm 26 of the bell crank lever 24, 26 is connected to the rack 22 by means of a rod 27. An arm 28 provided at the bell crank lever 24, 26 is pivotally connected to a rod 29. The rod 29 cooperates with bell crank levers 30 through which by means of guide rods 31 the bar 32 is moved. The jack sinkers are designated 33. Bar 32 serves to return the sinkers after they have been advanced by the slurcocks in the usual manner.

The slur bar 1 is reciprocated in the known manner by rotating the cam 3. If the stroke of the slurcocks is to be altered the handle 15 is adjusted, whereby the position of the guide block 11 of the bar 10 in the slot 7 is altered. According to the alteration of the effective length of the arm 6, the slur bar 1 and therefore the slurcocks 2 are moved over correspondingly longer or shorter distances.

The reduction of the slur bar stroke prevents moving the slurcocks beyond the end of the sinker bed 32. It would therefore be impossible for the bar 32 to press the sinkers 33 out of their working position. The cam 100

23, however, shifts the rack 22 so that the toothed drum 21 is rotated and the slurcocks 2 are moved out of their working position by means of the cranks 19 of the rod 18. 5 On account of the connection between the movement of the bar 32 and the rack 22, the bar 32 may freely press back the sinkers 33 after the slurcocks 2 have been retracted.

What I claim is:

- 10 1. In a flat knitting machine having a plurality of sinker beds and slurcocks for operating at the respective sinker beds, the combination with means to drive the said slurcocks, of means for adjusting the said driving means to vary the extent to which the slurcocks are driven and thereby the number of sinkers operated in any given bed.
- 15 2. In a flat knitting machine having a plurality of sinker beds and slurcocks for operating at the respective sinker beds, the combination with means to drive the said slurcocks, of means for adjusting the said driving means to vary the extent to which the slurcocks are driven and thereby the number of sinkers operated in any given bed and means for retracting the slurcocks at the end of the driving movement thereof to permit the withdrawal of the sinkers from the working line.
- 20 30 In testimony whereof I affix my signature.
RUDOLPH GRAEBER.
